UNITED STATES PATENT OFFICE.

CLINTON L. WOLFE, OF BROOKLYN, NEW YORK.

RESILIENT WHEEL.

1,203,674.

Specification of Letters Patent. Patented Nov. 7, 1916.

Application filed May 25, 1915. Serial No. 30,348.

To all whom it may concern:

Be it known that I, CLINTON L. WOLFE, a citizen of the United States, residing at Brooklyn, in the county of Kings and State of New York, have invented certain new and useful Improvements in Resilient Wheels, of which the following is a specification.

This invention relates to resilient wheels of the type employing inner and outer rims 10 with resilient spacing means between them.

One object of the invention is to develop a construction which will afford localized resiliency to relatively small areas of the outer rim, independently of the remainder 15 of said rim, so as to simulate more nearly the effect of a pneumatic tire; to which end, one feature of the invention consists in sub-dividing the outer rim into a large number of independent sections united by 20 pintles or other suitable hinging means, with their axes parallel to the axis of the wheel, so that a rubber tire supported on such rim, can yield in the immediate vicinity of the point at which it bears upon the 25 road surface without having to move any considerable portion of the rim; this effect being realized in greatest measure by having the resilient spacing means connected at the 30 pintles instead of at intermediate points of the rim sections.

Another object of the invention is to provide a driving connection between the inner and outer rims, which will be very substantial and unyielding circumferentially of the 35 wheel, as well as in the direction of its axis, but which will permit entire freedom of movement of the outer rim parts radially; also to embody these driving and sustaining 40 connections in a light but rigid structure, and to bring the same into coöperative relation with the rims through means that are very effective but simple in construction.

To these ends, another feature of the invention consists in mounting upon opposite 45 edges of the inner rim, annular plates extending radially a distance sufficient to overlap inner portions of the outer rim, and to provide said plates with radial grooves which receive the outer rim pintles and 50 guide them in their radial movements, while transmitting through them to the outer rim, the drive received from the inner rim.

A further feature relates to the construction of the resilient means interposed be- 55 tween the rims, which comprises a unitary device multiplied sufficiently to provide a

radially yielding support beneath each rim pintle; each of said resilient units comprising a spring whose outer seat is in the form of a stirrup carried by the pintle, and whose inner seat is upon the flange of a dash pot 60 radially set into the inner rim, and whose piston extends coaxially with the spring to present an additional resistance to the inward movement of the outer rim pintle and 65 the parts connected therewith.

A further object relates to the adaptation of the features of the invention already described in a wheel structure embodying a plurality of parallel treads, each mounted 70 upon an independent outer rim separately movable relatively to the inner rim; in which multiple tread adaptation, there is a common inner rim with one intermediate annular alining plate which serves in common 75 for both outer rims, and two outer alining plates serving to connect the common inner rim with the respective outer rims, and a separate annular series of resilient spacing units for each outer rim.

The above outline of the features of the invention where directed to details, is to be understood as relating to the exemplifications of the invention selected to illustrate its structural and operative characteristics, 85 and not as indicating the scope of the invention, for it is obvious that while all of the features above outlined and hereinafter described may enter into coöperation in the most desirable embodiment of the several 90 features of the invention, many of these features involve novelty *per se*.

The invention will be fully understood upon reference to the accompanying drawings, in which—

Figure 1 is a side elevation of a wheel disclosing one embodiment of the invention; the alining plate being partly in section to disclose interior parts. Fig. 2 is an edge view of the wheel shown in Fig. 1. Fig. 3 is a detail view of the upper portion of Fig. 1, in which one of the rim sections, one of the resilient units, and a portion of the alining plate are shown in section. Fig. 4 is a section on the line 4—4 of Fig. 3. Fig. 5 is a section on the line 5—5 of Fig. 3. Fig. 6 is a detail view of several of the outer rim sections. Fig. 7 is a sectional detail view of a double tread wheel construction. Fig. 8 is a detail view, in plan, showing a portion of the wheel shown in Fig. 7, the outer rim pintles being staggered in positions. Fig.

9 is a view similar to Fig. 7, showing a modification in which the corresponding pintles of the two outer rims are in alinement and integral. Fig. 10 is a detail view, in plan, 5 of the wheel shown in Fig. 9. Fig. 11 is a detail view showing the connection of the alining plates with the inner rim and the mounting of one of the resilient spacing units thereon. Fig. 12 is a detail view of 10 the movable clamp employed for securing the cushion tire to the outer rim.

Referring to Figs. 1 to 6, 1 represents a cushion tire, 2 an annular series of sections or members forming a rim for supporting 15 the same, provided with clencher jaws 3, 4, of which the jaws 3 are integral with the sections, while the jaws 4 are adjustable to develop clamping pressure upon the tire; said sections being united by hinges 5 having 20 pintles 5^a, and their clamping jaws which are fitted together by sockets 3^a and tongues 4^a are drawn together by screws 6, which enter notches in the inner side of the cushion tire or penetrates the same as may 25 be desired. 7 represents the inner rim which is supported by spokes 8 from any suitable hub construction 9.

To establish driving connection between 30 the rims 7 and 2 and sustain them against axial thrust, without resisting the radial movement of the outer rim, annular alining plates 10 are mounted upon the inner rim 7, as for instance by providing hollow ribs 10^a on the plates to receive lugs 7^a on the inner 35 rim and bolts 11 for securing said plates, and these hollow ribs 10^a extend radially outward in position to receive the pintles 5^a, so that while overlapping the outer rim and 40 permitting radial movement thereof, the plates prevent circumferential movement of said outer rim relatively to the inner rim.

Located between each pinte 5^a and the 45 rim 7, is a resilient unit comprising a compression spring 12 having a seat 13 for positioning it upon the inner rim, and a seat 14 carried by a stirrup 15 through which it receives inward radial load from the pinte 5^a. In addition to this spring, and mounted coaxially within it, there is preferably a limiting 50 cushion 16, against which the seat 14 may strike under extreme loads, and to further resist and graduate the effect of heavy 55 loads, a plunger 17 projects through the cushion 16 into the path of the movable seat 14 and carries upon its inner end, a piston 18, working in the dash pot 19 against a return spring 20, as well as a body of air that may be trapped in the dash pot. The dash pots 19 are conveniently mounted upon 60 the inner rim by setting them in radial openings in said rim and permitting them to rest upon their flanges 13, which provide seats for the springs 12.

When it is desired to embody the invention 65 in a multiple tread wheel such as illus-

trated in Figs. 7 to 10, each outer rim 2 as well as its accessory parts, including the resilient units 12 and their accessory parts, may be substantially as described in connection with Figs. 1 to 6, and so with the outer 70 alining plates 10 and their connections 7^a, 10^a, 11 and 5^a; but the inner rim 7^b is preferably supported on a double series of staggered spokes 8^b and carries an intermediate alining plate or flange 10^b integral therewith. 75

According to Figs. 7 and 8, the grooves 10^c, receiving the inner ends of pintles 5^a, are staggered or alternated in position on opposite sides of the flange 10^b, while in 80 Figs. 9 and 10, said flange is provided with through slots 10^d for the passage of the pinte 5^b, which serves in common for both outer rims.

I claim:

1. A wheel comprising inner and outer rims, one of which is made up of a circumferential series of sections joined to permit radial flexibility, a series of radially acting resilient spacing means located between the 90 rims, said spacing means comprising coil springs and pneumatic buffers concentrically placed; and alining plates overlying both rims; the joints between the sections embodying pintles parallel to the wheel axis; 95 said resilient means being connected to the sectional rim through the medium of said pintles; said pintles being circumferentially interlocked with but radially movable on said alining plates. 100

2. A wheel embodying in its structure resiliently spaced inner and outer rims, and alining plates overlying said rims; said alining plates being constructed with inwardly presented radial grooves, said outer 105 rim being constructed with lateral projections which enter and are radially movable in the outer portions of said grooves, said grooves being closed at their outer ends and adapted to limit the outward movement of 110 said projections, and said inner rim being constructed with lateral lugs which enter and are fixed in the inner portions of said 115 grooves.

3. A wheel comprising in its structure a 120 radially flexible sectional outer rim having pintles hinging its parts together and projecting laterally beyond the same, an inner rigid rim having laterally presented lugs, resilient spacing means interposed between 125 the rims, said spacing means comprising coil springs and pneumatic buffers concentrically placed; and alining plates overlying said rims and having inwardly presented radial 130 grooves fitting at their inner portions upon the lugs of the inner rim, and receiving the pintles with freedom of radial movement in their outer portions; said plates being bolted to the inner rim through said lugs.

4. In a resilient wheel comprising flexible 135

- and rigid rims, with a series of resilient spacing members between them; buffers embodied in said resilient members, said resilient members comprising coil springs, and 5 said buffers being concentric with said springs; dash-pots also positioned concentric with said springs, pistons in said dash-pots having rods projecting into the paths of parts moving with the flexible rim, and said 10 buffers surrounding said piston rods and serving as limit stops for the flexible rim.
5. In a resilient wheel comprising flexible and rigid rims, with a series of resilient spacing members between them; buffers embodied in said resilient members, said resilient members comprising coil springs, and 15 said buffers being concentric with said springs; dash-pots also positioned concentric with said springs, pistons in said dash-pots 20 having rods projecting into the paths of parts moving with the flexible rim, and said buffers surrounding said piston rods and serving as limit stops for the flexible rim, said dash-pots being constructed with seats 25 for the springs.
6. In a resilient wheel comprising flexible and rigid rims, with a series of resilient spacing members between them; buffers embodied in said resilient members, said resilient members comprising coil springs, and 30 said buffers being concentric with said springs; dash-pots also positioned concentric with said springs, pistons in said dash-pots having rods projecting into the paths of 35 parts moving with the flexible rim, and said buffers surrounding said piston rods and serving as limit stops for the flexible rim, said dash-pots being seated in radial perforations in the rigid rim, and provided with axial and peripheral flanges forming seats, 40 respectively for the buffers and for the springs.
7. A resilient wheel comprising an inner rim, a plurality of independent outer rims, and separate circumferential series of resilient spacing means between the inner rim and the respective outer rims, there being 45 alining plates carried by the inner rim and overlapping and sustaining the outer rims, one alining plate serving in common for two 50 rims where it occurs intermediate thereof; said outer rims comprising hinged sections having protruding pintles, and said alining plates having radial grooves to receive said 55 pintles, said spacing means comprising spiral springs and pneumatic buffers.
8. A resilient wheel comprising an inner rim, and two independent outer rims, and separate circumferential series of resilient spacing means between the inner rim and 60 the respective outer rims, said spacing means including spiral springs and pneumatic buffers, there being alining plates carried by the inner rim and overlapping and sustaining the outer rims; one of said alining 65 plates being intermediate of the two outer rims and serving in common for both; said outer rims comprising hinged sections having protruding pintles, and said alining plates having radial grooves to receive said 70 pintles; the pintles and the grooves in the alining plates for receiving them being alternated or staggered in positions upon the two outer rims.

The foregoing specification signed at 75 Brooklyn, New York, this 4th day of May, 1915.

CLINTON L. WOLFE.
